UNITED STATES PATENT OFFICE.

RICHARD S. SHAFFER, JOHN KING ADAMS, AND GEORGE W. HUNTER, OF ALBANY, MISSOURI.

CAR-COUPING.

SPECIFICATION forming part of Letters Patent No. 325,873, dated September 8, 1885.

Application filed June 30, 1885. (No model.)

To all whom it may concern:

Be it known that we, R. S. SHAFFER, J. K. ADAMS, and G. W. HUNTER, of Albany, in the county of Gentry and State of Missouri, 5 have invented an Improved Car-Coupler, of which the following is a specification.

The invention relates, generally, to automatic car-couplings, and the special objects thereof are to lessen the danger incurred by 10 brakemen in uncoupling cars, and to cause the coupler and draw-head to work properly.

Figure 1 of the drawing is a perspective view showing the connection of the coupler-cap with levers on the car, and the device by 15 whose aid the coupler is held, so as not to couple when two cars come together, unless it is intended for them to do so. Fig. 2 is a vertical sectional view of the coupler with its cap, yoke, and spring. Fig. 3 is a plan view 20 of the frame in which the draw-head works, showing the side springs, which always bring it back into alignment with the axial longitudinal line of draft.

In the drawings, A represents the draw-head, having the rear end of its shank held 25 by a vertical pivot, a, passing through two horizontal cross-pieces, b b, of the draw-head frame B. The draw-head shank also passes through a front slot or opening, b', much 30 wider than itself, so as to allow for lateral play.

In order to keep the draw-head in the proper line of draft, we employ two plate-springs, C C, one on each side of the draw-head shank. These springs will yield where 35 the track runs on a curve, and then bring the draw-head back to its normal position.

D D are screw-stops, which may be adjusted to or from the front ends of springs C C, 40 so as to regulate the lateral movement of the draw-head. The latter has the ordinary inside cavity, a', and the upper slot, a', together with a cross-pivot, a''. On this turns the coupler E, which is beveled in front in 45 the well-known way, so that it will be lifted by the inward push of the link. This sort of automatic coupler has been long known to the public, but we attach to the top thereof a cap, e, extended laterally so as to be flush 50 with the sides of draw-head. To the sides of

this cap we attach the yoke e', which straddles the draw-head, and connect the bottom of this with the rear of draw-head by a flat spring, F, whose tension, if unobstructed, will bring down and there hold the coupler 55 E, but will yield to the inward pressure of the link. The object of this is to couple instantaneously after the front of link has passed the coupler, a result which the gravity-coupler often fails to produce. 60

G is a chain affixed to the top of cap e, and having a long branch, g, and a short one, g', the former connecting with a grooved cam or eccentric, H, on shaft h, and the latter with a shaft, J, carrying a detent, j, which works 65 in a notch, h', on the underside of cam H.

H' is an arm on one end of cam-shaft, and extending to or above the top of car, so that the brakeman can uncouple the car and keep the same uncoupled as long as may be desirable. 70 Thus he can not only use his brake, but may likewise uncouple his car without descending from the top thereof. He can stand on the ground or on his ladder while uncoupling, may do it from the top or from either side, and all without ever placing his life in danger.

Having thus described our invention, what we claim as new, and desire to protect by Letters Patent, is— 80

1. A pivoted coupler having the cap e, and connected with a spring, F, by the yoke e', whereby the coupler will yield to the link, allow it to enter, and then be forced down into the link-slot by said spring, as described. 85

2. The combination, with a pivoted coupler, of a top chain having one long and one short branch, a shaft having cam and crank-arm, and a shaft having detent, whereby the brakeman, by operating the crank-arm, can 90 raise the coupler out of and above the link, raise a detent to fit in a notch under cam, and hold up the coupler, as described.
